UNITED STATES PATENT OFFICE

109,978

DESIGN FOR A DANCING DOLL

Clarence Leon Craven, Detroit, and Silvester Ciccone and Jay G. Miller, Highland Park, Mich.

Application March 3, 1938, Serial No. 75,562

Term of patent 7 years

To all whom it may concern:

Be it known that we, Clarence Leon Craven, a citizen of the United States, residing at Detroit, in the county of Wayne and State of Michigan; Silvester Ciccone, a citizen of the United States, residing at Highland Park, in the county of Wayne and State of Michigan; and Jay G. Miller, a citizen of the United States, residing at Highland Park, in the county of Wayne and State of Michigan, have invented a new, original, and ornamental Design for a Dancing Doll, of which the following is a specification, reference being

had to the accompanying drawing, forming part thereof.

Fig. 1 is a front elevational view of a dancing doll, showing our new design.

Fig. 2 is a rear elevational view.

Fig. 3 is a side elevational view.

We claim:

The ornamental design for a dancing doll, as shown.

CLARENCE LEON CRAVEN.
SILVESTER CICCONE.
JAY G. MILLER.
